UNITED STATES PATENT OFFICE.

HERBERT ETHERIDGE, OF WIMBLEDON PARK, ENGLAND, ASSIGNOR TO THE BAR-LOCK
TYPEWRITER COMPANY LIMITED, OF LONDON, ENGLAND.

FEED MECHANISM FOR TYPE-WRITERS.

1,118,406.

Specification of Letters Patent. Patented Nov. 24, 1914.

Application filed May 23, 1914. Serial No. 840,475.

To all whom it may concern:

Be it known that I, HERBERT ETHERIDGE, a subject of the King of England, residing at Wimbledon Park, in the county of Surrey, England, have invented certain new and useful Improvements in Feed Mechanism for Type-Writers, of which the following is a specification.

This invention relates to the feed mechanism for the platen carriages of typewriters and has for its object to provide an improved form of such mechanism.

The present invention consists in the combination in a typewriter escapement mechanism of an escape-wheel, a pivoted pawl and ratchet, one of which members moves with the escape-wheel, and the other with the feed pinion for the carriage, and means for swinging the pawl about its pivots to disengage it from the ratchet at will to free the escape-wheel, said means being so disposed as not to interfere with the pivotal movement of the pawl when permitting backward movement of the carriage.

The escapement wheel may be carried on a spindle having a pinion thereon which meshes with the platen-carriage rack of the typewriter, the escapement wheel being free to rotate on the spindle and operatively connected with the spindle by the ratchet and pawl, a back-spacing pinion being also mounted on the spindle and provided with a key-operated pawl for actuating the back-spacing pinion.

The ratchet and pawl connection between the spindle and the escapement wheel may comprise a ratchet wheel mounted on the escapement wheel, whereof the ratchet teeth project laterally from the wheel parallel with the axis of the spindle, a U-shaped pawl-member pivoted transversely on the spindle and having a segmental series of teeth at the base of the U to engage the ratchet wheel on one side of the pivot and means engaging the free ends of the U on the other side of the pivot for operating the pawl.

The pawl may be actuated by a plate surrounding the escapement wheel spindle and adapted by movement axially of the spindle to engage the free arms of the pawl to operate it; this plate may be operated independently by the tabulator key or keys and by the carriage release lever.

In the accompanying drawings—Figure

1 is a view of the escapement mechanism from the rear of the machine; Fig. 2 is a plan in section on the line 2—2 of Fig. 1, and Fig. 3 is a perspective view of a detail.

Like reference letters indicate like parts throughout the drawings.

The spindle A is mounted in bearings A', A² in the frame of the machine and carries at its upper end a pinion B meshing with the rack on the platen carriage. An escapement wheel C is carried on a sleeve C' loose on the spindle A and on the upper side of the wheel C is a crown ratchet wheel C² whose teeth C³ extend in a direction parallel with the axis of the spindle A. A pawl-member D is mounted on a pivot D' transversely disposed on the spindle A. The pawl-member D is of U-shape and it is pivoted about the middle of the length of each arm of the U. The bottom of the U is provided with a series of teeth D³ shaped to conform to the ratchet teeth C³ on the wheel C² and a spring D⁴ mounted on the pivot pin D' is arranged to hold the teeth D³, C³ normally in engagement.

The lower end of the spindle A has mounted fast on it a back-spacing pinion E and a pawl E' is provided to operate this pinion and feed it back in steps of one tooth each. This pawl is operated by the link 85 and lever connections E², E³, E⁴, Fig. 2, from a key conveniently situated on the front of the machine. It will be understood that the pawl E' is arranged to feed the pinion E in the reverse direction to that in which it normally travels under the control of the letter-spacing mechanism.

The means for releasing the pawl-member D from engagement with the ratchet wheel C² comprises a plate F surrounding the spindle and carried on two arms F' suitably guided in the framework of the machine. The plate is normally held up out of engagement with the pawl-member by the spring F². Above the ends of the arms F' there is disposed on the platen carriage a rod G which is capable of being depressed by the carriage-release lever G'. A spring-controlled detent C⁴ engages the escapement wheel C and prevents it from being turned backward.

The tabulator keys, of which there are provided a number corresponding with the number of tabulator stops on the platen carriage, are each connected to levers H which 110

are arranged to bear on the upper side of the plate F and depress it when a tabulator key is depressed.

It will be appreciated that the hereinbefore described construction of pawl-member D and its operating plate F is such that although the pawl-member is carried around with the spindle it can be engaged and operated in any position in its rotation by the plate F; also that the provision of a segmental series of teeth D³ on the pawl instead of only a single tooth diminishes the wear and increases the reliability of the mechanism.

15 The operation of the mechanism is as follows:—The platen carriage is fed along in the ordinary manner by a spring under the control of the escapement wheel C. The rack on the platen carriage engages with the 20 pinion B on the spindle, thereby causing it to rotate and carry with it the pawl-member D which normally engages the ratchet teeth C³ and carries the escapement-wheel around with it. The movement of the escapement-wheel is controlled by dogs K operated by the key-levers or space-bar. When it is required to return the platen carriage to begin another line, it is pushed back and the teeth D³ of the pawl ride over the teeth 25 C³ of the ratchet wheel, so that this return motion is permitted and the escapement-wheel C remains stationary.

If it is required to set the platen carriage back by one or two spaces the back-spacing key is depressed and the pawl E' is thereby brought into engagement with the pinion E causing it to turn the spindle back by the required amount. The pinion D is fast on the spindle and by its engagement with the 30 platen carriage rack it moves the platen carriage back the required amount. During this movement the teeth D³ of the pawl again ride over the teeth C³ of the ratchet wheel C². The spring-controlled detent C⁴ 35 prevents backward rotation of the escapement-wheel C. This is provided because the friction of the pawl riding backward over the ratchet-teeth may be sufficient to carry the escapement-wheel back until its 40 teeth engage with the other side of the dog which is holding it. When this occurs the pawl teeth D³ would not engage in the correct position with the ratchet-teeth C³, and the platen carriage, which has been moved 45 back, will move forward again to take up this movement of the escapement wheel.

When the tabulator mechanism is operated the teeth D³ on the pawl are lifted out of engagement with the teeth C³ and the carriage is free to travel under the action of its driving spring until the tabulator stops 50 come into engagement. During this movement the spindle rotates freely, as the pawl is held out of engagement, owing to the 55 plate F engaging the arms D⁶ at all times

during their rotation. A similar action occurs when the carriage-release lever G' is operated. The pawl is held out of engagement and the carriage is free to travel through any required distance.

It will be understood that throughout this specification where the term "typewriter" is used any typing mechanism, such for example as is sometimes employed in an adding machine, is intended to be included.

What I claim as my invention and desire to secure by Letters Patent is:—

1. In a typewriter-escapement-mechanism the combination of, a spindle, a carriage-feed-pinion thereon, an escapement-wheel thereon, one of the elements on the spindle being fast with the spindle, a ratchet-and-pawl operatively connecting the pinion and the wheel, and means for swinging the pawl about its pivotal axis to disengage it from the ratchet at will, said means not interfering with the free pivotal movement of the pawl when riding over the ratchet, substantially as set forth.

2. In a typewriter-escapement-mechanism the combination of a spindle, a carriage-feed-pinion fast thereon, an escapement-wheel loose thereon and having in addition to the escape teeth a set of ratchet teeth, a pawl carried around with said spindle and pivotally mounted thereon to coöperate with said ratchet-teeth in such manner as to operatively engage it with the spindle, means engaging said pawl and movable to swing it pivotally out from engagement with the ratchet-teeth, said means not interfering with the free pivotal movement of the pawl when riding over the ratchet, substantially as set forth.

3. In a typewriter-escapement-mechanism the combination of a spindle, a carriage-feed-pinion fast thereon, an escapement-wheel loose thereon, and having in addition to the escape-teeth a series of ratchet-teeth projecting parallel with the axis of said spindle, a U-shaped pawl-member pivoted transversely on said spindle and having on one side of the pivot a segmental series of teeth at the base of the U to engage the ratchet-teeth and means engaging the free ends of the U-shaped pawl on the other side of the pivot and movable to disengage it from the ratchet-teeth at will, said means not interfering with the free pivotal movement of the pawl when riding over the ratchet, substantially as set forth.

4. In a typewriter-escapement-mechanism the combination of a spindle, a carriage-feed-pinion fast thereon, an escapement-wheel loose thereon, having in addition to the escape-teeth a series of ratchet-teeth, a pawl rotating with said spindle and pivoted thereon, coöoperating with said ratchet-teeth, a plate surrounding said spindle and movable axially thereof to engage the free end

of the pawl and swing it out of engagement with said ratchet, substantially as set forth.

5. In a typewriter the combination of a spindle, a carriage-feed-pinion thereon, an escapement-wheel thereon, a ratchet-and-pawl operatively connecting the wheel and pinion, means for swinging the pawl about its pivotal axis to disengage it from the ratchet, a carriage-release lever operatively 10 connected to said means, and tabulator-keys

also operatively connected to said means, substantially as set forth.

In testimony whereof I have signed my name to this specification in the presence of two subscribing witnesses.

HERBERT ETHERIDGE.
